UNITED STATES PATENT OFFICE.

MARTIN JELALIAN, OF CRANSTON, RHODE ISLAND.

DEVICE FOR WALKING UPON THE SURFACE OF THE WATER.

1,264,523.

Specification of Letters Patent. Patented Apr. 30, 1918.

Application filed November 13, 1917. Serial No. 201,805.

To all whom it may concern:

Be it known that I, MARTIN JELALIAN, a citizen of the United States, residing at the city of Cranston, in the county of Providence and State of Rhode Island, have invented certain new and useful Improvements in Devices for Walking Upon the Surface of the Water, of which the following is a specification.

- 10 The object of the invention is to provide a device of such character that will easily permit a person to walk upon the surface of the water in a most safe and successful manner.
- 15 The device is provided with a gas balloon in order to assist in lifting or to give additional buoyancy to the operator and to enable the latter to slidably walk through the water.
- 20 The invention consists of the special features of construction and combination of parts as hereinafter described and claimed.

In describing the invention in detail, reference is had to the accompanying sheet of drawings forming a part of this specification, in which:

Figure 1— is a front view of the improved device, showing the parts of the same in their relative position.

Fig. 2— is a view of the rear of the device.

Fig. 3— is a side perspective view of one of the foot support members.

35 Fig. 4 is a bottom perspective view of Fig. 3.

Fig. 5— is a detail view showing the joints of the foot support members separated.

40 Fig. 6— shows the joints of Fig. 5 in their engaged position.

Referring to the drawings, numeral —1— designates a gas balloon having circumferentially arranged rope connections —2— and also rope connections —3— extending from the central portion of the gas balloon and connected at a point as at —4—. Rope connections —5, 5— extend from the central portion of the gas balloon —1— and 50 have their ends connected to the upper portion of a ring —6—. Ropes —9, 9— have their upper ends attached to the ring —6— and the lower ends thereof suitably connected to the upper portion of the detachable abdominal strap —12— secured

to the abdominal part of the operator —10—.

The ring —6— is provided with a wire netting —7— and has a layer of canvas —8— secured to the netting in order to serve as a plane or to react against the atmosphere; cylinders —9', 9'— are carried beneath the said plane and are provided with strap connections —9², 9²— secured thereto.

Said plane is also designed to serve as a float for the operator in case the gas bag should collapse. The utility of arranging the gas bag is that the same will assist in the lifting operation and also will keep the operator in erect position.

A pair of foot boards —16', 16"— is detachably secured to the foot part of the operator —10— and each has an integral main foot strap —19'— upon the top of the same and also a pair of air containers —17, 17— secured upon the bottoms thereof by means of straps —17⁴, 17⁴— in order to give additional buoyancy to the operator —10— and to float upon the surface 80 of the water.

Each foot strap —19', 19"— is also provided with attaching strap connections —19, 19— for attaching to the lower leg parts of the operator or user —10— as shown by Figs. 1, 2 and 3.

A hand support —17²— is adapted to support the operator and designed to keep the latter in perfectly erect position and said support has a rectangular shaped board —18'— secured at its lower end, and the same has a pair of air containers or lateral buoyant members —19⁶, 19⁶— secured upon the bottom thereof by means of straps —17⁴— and said buoyant members are adapted to float upon the surface of the water in the manner shown in Fig. 1.

Thus it will be readily understood that the arrangement of the parts of the device as described will enable a person to slidably walk upon the surface of the water in a perfectly safe and successful manner.

Thus having described my invention, what I claim as new and desire to secure by Letters Patent is:

1. In a device of the character described, a means for walking upon the surface of the water comprising a gas balloon having a main plane suspended therefrom, said plane consisting of a metallic ring provided with

a wire netting a layer of canvas secured to the same, buoyant cylinders carried beneath said plane and having integral strap connections secured thereto, and said cylinders 5 adapted to float upon the surface of the water in case the gas bag should collapse, rope connections extending from said ring and the free ends thereof attached to the upper portion of an abdominal strap provided 10 with strap connections for securing it to the abdominal part of the operator.

2. In a device of the character described, a means for walking upon the surface of the water comprising a gas balloon carrying a main flat circular plane suspended therefrom, and said plane consisting of a metallic ring provided with a wire netting and a layer of canvas secured thereto; rope connections extending from said gas balloon 15 and the free ends thereof connected to the perforations formed at the upper end of said ring, and also rope connections extending from the lower end of the latter and connected to an abdominal support carried by 20 the operator, a pair of foot board members, one of the same having a flat sided outwardly projecting portion adapted to have sliding movement within the other, and each of said board members provided with an integral foot strap upon the top of the same 25

and having strap connections for securing said board members to the lower leg parts of the operator, a pair of lateral buoyant cylinders carried beneath each of said foot board members and provided with strap 30 connections for securing said cylinders upon the bottoms of the board members, and said cylinders adapted to float upon the surface of the water. 35

3. In a device of the character described, a means for walking upon the surface of the water consisting of a gas balloon and an abdominal strap, a pair of slideable foot board members secured to the foot part of the operator and each having air containers secured upon the bottoms of the same, a hand support for the operator designed to keep the latter in perfectly erect position, and said support having an integral rectangular shaped board at its lower end, a pair of 40 buoyant cylinders carried beneath the same and provided with strap connections for securing the cylinders thereto. 45

In testimony whereof I affix my signature in presence of two witnesses.

MARTIN JELALIAN.
